SHOEMAKER'S CLAMP

Edward A. McLane, Elko, Nev.

Application October 5, 1945, Serial No. 620,445

1 Claim. (Cl. 12—103)

1

The present invention relates to clamps for cementing half-soles to shanks.

In the present day method of repairing shoes it is a customary practice to cut away the worn sole and cement a new half-sole to the shank which is skived for the overlapping new half-sole.

One of the objects of the invention is to produce a clamp to hold the cemented overlapping new half-sole and shank firmly in position until the cement is dry and the two parts are bound together.

Another object of the invention is to provide a clamp of the class described which can be constructed at little cost and is of simpler and more compact construction than that disclosed in prior devices.

With the foregoing and other objects and advantages in view, the invention consists of the novel construction and arrangement of parts hereinafter described and claimed.

In the accompanying drawings illustrating the invention:

Figure 1 is a side elevation of the device partly in section.

Figure 2 is a horizontal section on line 2—2 of Figure 1.

Figure 3 is an end elevation of the device.

Figure 4 is a transverse section of the device as applied in practice.

Like numerals in the description and drawings designate the same parts of construction.

The clamp consists of an upper plate 1 and a lower plate 2 of metal slightly bowed longitudinally, and of suitable dimensions for the purpose as hereinafter stated. The lower plate is beveled or inclined from front to rear on its under side, as at 3, in Figure 4, so that it will easily wedge under the skived shank 5 of a shoe.

Both ends of each clamp plate are curved, as at 7, to produce divergent arms when the plates are assembled and the arms on the upper plate are provided with vertical elongated holes 8 for the reception of elongated and threaded bolts 9.

The ends of the arms of the lower plate 2 are 45 curled under to form shoulders 10.

Levers 11 bifurcated at their inner ends are fulcrumed on pins or studs 12 which project laterally from the lower ends of bolts 9. Pivotally mounted on the bifurcated end of levers 11 50 are stirrups or hooks 13 with wide jaws adapted to engage shoulders 10.

A compression spring 14 is mounted between

2

washers on each bolt 6 and is adjusted by a wing nut 15. When the half-sole and shank are cemented and emplaced between the plates of the clamp, the stirrups or hooks 13 are engaged with shoulders 10 in arm 7. After the work is thus positioned, the two levers are depressed until their pivotal connections with the stirrups or hooks pass above the fulcrum point of the levers and thus lock the two plates in firm engagement with the work.

The job can now be put aside until the cement has dried. In view of the fact that these clamps are inexpensive, a shoe repairman can afford to provide himself with a sufficient number of them 15 to take care of many such repair jobs. Not many are required for a shop of ordinary work capacity. Furthermore, these inexpensive clamps obviate the installation of an expensive bench device to do such work with slower progress.

20 Having thus described my invention, what I claim as new and desire to secure by Letters Patent is:

A shoemaker's clamp consisting of an upper and a lower metal plate slightly curved longitudinally wherein both ends of each clamp plates are curved to form divergent arms when the plates are assembled, the upper plate arms being provided with vertical holes, and the lower plate arms are curled under to form a shoulder on each 25 lower plate arm, a threaded bolt arranged slidably in each hole, a wing nut on each bolt above the upper arm, a helical spring surrounding each bolt between the upper arm and the corresponding nut, a pair of studs extending laterally from each bolt underneath the upper arm, a lever having a bifurcated inner end, pivotally mounted on each pair of studs, and a stirrup hook having a wide jaw pivotally mounted on the bifurcated end of each lever and adapted to engage the corresponding shoulder on the lower plate arm with the said jaw.

EDWARD A. McLANE.
